(57) **CLAIM**

The ornamental design for a curved light, as shown and described.

DESCRIPTION

FIG. 1 is a perspective view of a curved light according to the present invention shown mounted to a tri-pod stand; FIG. 2 is a perspective view thereof, shown mounted to a pole and table clamp;

FIG. 3 is a left side view thereof;

FIG. 4 is a right side view thereof;

FIG. 5 is a top view thereof;

FIG. 6 is a bottom view thereof;

FIG. 7 is a front view thereof;

FIG. 8 is a rear view thereof; and,

FIG. 9 is a cross-section view taken along line 9-9 of FIG. 4.

Portions of the design shown in broken lines form no part of the claimed design.

1 Claim, 4 Drawing Sheets
